UNITED STATES PATENT OFFICE.

FRANK W. RAICY, OF MODESTO, CALIFORNIA.

SAWDUST SOAP.

1,387,804.

Specification of Letters Patent. Patented Aug. 16, 1921.

No Drawing.

Application filed February 2, 1920. Serial No. 255,670.

To all whom it may concern:

Be it known that I, FRANK W. RAICY, citizen of the United States, residing at Modesto, in the county of Stanislaus and

5 State of California, have invented certain new and useful Improvements in Sawdust Soap, of which the following is a specification.

The invention relates to a soap and the 10 method of producing the same.

It has long been recognized that sawdust or wood fiber when mixed with a detergent produces a highly satisfactory soap for the removing of grease, dirt, or the like, from 15 the body of a person, as sawdust possesses a peculiar action on the dirt or the like, readily loosening or removing the same. The use of sawdust soap, with all the advantages of sawdust, has been very unsatisfactory, and 20 practically abolished, for the reason that when the sawdust is incorporated with the soap, air serves to rapidly decompose the same. It has been found that after a very brief period, wood fiber or sawdust that is 25 incorporated in a body of soapy material decays or decomposes, which renders the soap entirely useless.

It is an object of the present invention to provide a sawdust soap and the method of 30 making the same wherein the sawdust is protected in the body of the soap against decomposition or the like for indefinite periods. With the foregoing conception in mind, the invention preferably comprises 35 a soap containing sawdust or wood fiber particles which are enveloped or sealed from the air by an agent impervious to the air to prevent a decomposition of the sawdust after a period of standing.

40 The invention aims to provide a wood fiber or sawdust soap of a substantially solidified or solid nature containing inherent moisture or water which enables the soap when applied to the hand of the user and subjected 45 to a slight friction or rubbing action to produce its own necessary moisture to facilitate a cleansing action eliminating the use of extraneous water which is necessary in the use of sawdust soaps of which I 50 am at present aware. This manifestly enables the soap to be used at any time, and under any conditions where a source of water is not present. To provide a sawdust soap containing inherent water or moisture, 55 it is of course necessary to envelop or protect the wood fiber from the detrimental

action of the air, and the present invention contemplates the surrounding or inclosure of such saturated fiber particles with an impervious fragile envelop.

60

The present soap contains the fine particles of sawdust or wood fiber and is substantially solid, or having the appearance of solid globules of soapy material, which globules and sawdust particles are thoroughly enveloped by a fragile coating of an impervious agent such as paraffin or the like, which is readily ruptured when the soap is applied to the hands of the user, releasing the somewhat liquid soapy substances, and 70 also the absorbed moisture of the sawdust, which produces sufficient water or moisture to enable a complete cleansing action to be accomplished without the application of extraneous water. These minute globules extend 75 throughout the body of the soap and like the protecting covering for the wood fiber incorporated with a soapy mixture, they are readily broken or ruptured when the soap is used, but remain intact in the body 80 of soap for indefinite periods, if not subjected to a compressing or frictional action.

In carrying out the present invention to produce a soap, sawdust that is preferably cut with the wood grain is thoroughly dried 85 and mixed with a quantity of soap chips, water, salsoda and an impervious coating agent such as paraffin, beeswax, or the like, and subjected to a heat treatment or boiling action causing a homogeneous mixture 90 of the entire mass. After being so treated, the mass is then discharged into an agitator containing cold water or another liquid, and subjected to a stirring or agitating action. The subjection of the previously 95 heated mass to the cold liquid in the agitator causes the protective agent such as the paraffin or beeswax which has been heated to congeal or solidify, the agitation forming minute globules of soapy water being 100 inclosed by the paraffin, while the sawdust which is also saturated with soapy water is surrounded and completely protected from the air by a protective coating of paraffin. The proper agitation of the mass 105 apparently solidifies the same, the treated material taking the form of a soap that is to the eye solid, yet contains throughout its body many minute or small globules of soapy water and sawdust, all of which are 110 covered by the protective coating of hardened paraffin, which will not rupture un-

less subjected to a compressing or frictional action. The soap after being agitated is collected in its somewhat solid state, being as before stated, composed of globules of 5 soapy water enveloped by the paraffin and wood fiber which is completely protected from the decomposing action of the air, although the same is saturated, by the said envelopes of paraffin that have of course 10 hardened or congealed. The soap when in this form may be packed in cans, boxes or any preferred form of container, and will remain in its original state for indefinite periods, being as before stated to the eye, a 15 solid or solidified compound, yet containing in itself such moisture as will enable the hands or the like to be thoroughly cleansed when the soap is applied thereto and subjected to a rubbing or frictional action 20 which ruptures the fragile coatings of the soapy globules and the sawdust, producing the necessary moisture or water to insure such a cleansing action. This eliminates the use of extraneous water and likewise enables a sawdust soap to be employed wherein in the sawdust will neither decompose or lose its effective cleansing action by long standing which is the difficulty now encountered in the use of the sawdust soap of 30 which I am now aware. It might be stated that when the soap is applied to the hands of the user the sawdust, after having its protective coating of paraffin destroyed, possesses the same affinity for dirt as the dried sawdust, serving to loosen and gather any and all dirt with which it encounters.

For producing the present product the following formula may be followed, but of course this formula is only given for the 40 purpose of illustrating the invention, and is subject to many variations with respect to the quantities of the different ingredients and the like.

Assuming that it is desired to produce 45 approximately 13 pounds of the soap, about six pounds of dried sawdust, preferably cut with the grain of the wood, is mixed with one-half pound of soap chips, three ounces of paraffin, one-half pound of salsoda and 50 three quarts of water. The mixture is then subjected to a heat treatment to bring the same to a boiling point which causes a thorough incorporation or homogeneous mixture of the different constituents of the soap, and 55 after such boiling the entire mass is then introduced to a receiver containing an additional supply of approximately three quarts of water and thoroughly agitated. The introduction of the heated mass to the receiver and the agitation of the same results in a hardening or congealing of the paraffin which serves to surround or coat minute particles of soapy water and sawdust which is also thoroughly saturated with soapy water

or the like, so that after a determined agitation the entire mass takes the appearance of a solid substance, which is then introduced to suitable containers for packing. The substance, however, contains the inherent water, but such water is as before stated, 65 thoroughly surrounded with its soapy mixture by the paraffin while the sawdust is likewise surrounded by such a coating, and distributed substantially uniformly throughout the body of the soap. 70

I preferably employ a sawdust made from white sugar pine or white fir wood, as the same contains no detrimental rosin, and should also be cut with the grain so as to have no tendency to scratch the hands of 80 the user when the soap is being employed. While I have disclosed as a protecting agent for the soapy globules and the sawdust particles, paraffin, or beeswax, it will be understood that other ingredients may be freely 85 employed so long as they have the tendency of congealing or hardening when subjected to the cold water, and are of such a fragile nature as to be easily ruptured when the soap is used. 90

Having thus described the invention, what I claim is:

1. A cleansing compound comprising a paste, containing particles of water saturated wood fiber, and protective fragile coatings 95 surrounding said particles, a soap distributed in said paste, and soapy water globules incorporated in the paste and surrounded by fragile coatings, the quantity of water contained in the paste being sufficient to 100 permit the paste to be used for a cleansing operation without employing extraneous water.

2. A cleansing compound, comprising a paste containing water saturated sawdust 105 surrounded by fragile coatings impervious to air, a soap incorporated in said paste, the inherent water in the paste being sufficient to permit the paste to effect a cleansing operation without applying water from an 110 extraneous source.

3. A cleansing compound comprising a paste containing water saturated sawdust, and protective coatings of a fragile nature surrounding said sawdust particles, a soap 115 incorporated in the paste, and soapy water globules distributed throughout the paste and surrounded by destructible coatings impervious to air, for the purpose described.

4. A cleansing compound comprising a 120 paste containing water saturated sawdust, a soap incorporated in the paste, said paste having sufficient inherent water protected from evaporation by destructible coatings to permit a cleansing operation without the 125 application of extraneous water.

In testimony whereof I affix my signature.
FRANK W. RAICY.
